UNITED STATES PATENT OFFICE.

CLARENCE WRIGHT, OF RACINE, WISCONSIN, ASSIGNOR TO RACINE AUTO TIRE COMPANY, OF RACINE, WISCONSIN, A CORPORATION OF WISCONSIN.

DESIGN FOR A VEHICLE TIRE OR CASING.

53,479.

Specification for Design.

Patented June 17, 1919.

Application filed March 25, 1919. Serial No. 285,104. Term of patent 14 years.

To all whom it may concern:

Be it known that I, CLARENCE WRIGHT, a citizen of the United States of America, residing at Racine, in the county of Racine and State of Wisconsin, have invented a new, original, and ornamental Design for a Vehicle Tire or Casing, of which the following is a specification, reference being had to the accompanying drawings, forming part thereof.

In the drawings:—

Figure 1, is a plan view of a portion of a tire or casing embodying my new design.

Fig. 2, is a cross section.

I claim:—

The ornamental design for a vehicle tire or casing, substantially as shown.

CLARENCE WRIGHT.
